UNITED STATES PATENT OFFICE

FREDERICK W. ROETTGES, OF BROOKLYN, NEW YORK, ASSIGNOR TO LIGHTING APPLIANCE COMPANY, INC., OF NEW YORK, N. Y.

DESIGN FOR A BODY PLATE FOR LIGHTING FIXTURE OR ARTICLE OF SIMILAR NATURE

Application filed January 30, 1930, Serial No. 24,350, and in Canada December 4, 1929. Term of patent $3\frac{1}{2}$ years.

To all whom it may concern:

Be it known that I, FREDERICK W. ROETTGES, a citizen of Germany, residing in Brooklyn, New York, in the county of Kings and State of New York, have invented a new, original, and ornamental Design for a Body Plate for Lighting Fixture, or Article of Similar Nature, of which the following is a specification, reference being had to the accompanying drawing, forming a part thereof, in which the portions shown in broken outline involve a mere repetition of the com-

pleted portions more fully illustrated in solid lines.

Figure 1 is a plan view of a body plate for lighting fixture showing my new design.

Figure 2 is a perspective view thereof.

I claim:

The ornamental design for a body plate for lighting fixture, or article of similar nature, as shown and described.

In testimony whereof I affix my signature.

FREDERICK W. ROETTGES.
